UNITED STATES PATENT OFFICE

DAVID W. JOHNSON, OF CHICAGO, ILLINOIS

CHECK WRITER

Application filed May 11, 1928. Serial No. 276,872.

This invention relates to improvements in check writers and pertains particularly to an improved and advantageous mechanism for selectively setting the type at the printing position.

The general object of the invention is the provision of a check writer which may be embodied in a device of small size, yet possesses an unlimited range in respect to the amounts which may be written by it, and which is particularly qualified for rapid and certain operation.

A more particular object is the provision of such a device wherein the selective setting 15 of the type may be accomplished quickly and with certainty.

Other and further objects will be pointed out or indicated hereinafter, or will be apparent upon an understanding of the invention or its employment in practice.

In the drawings forming a part of this specification I show one embodiment of the invention, but it is to be understood that this is presented for the purpose of illustration 25 only, as the particular construction and arrangement shown may be departed from without departing from the spirit of the invention or the scope of the appended claims.

In the drawings 30 Fig. 1 is a top view of a small check writer in which the invention is embodied,

Fig. 2 is a side sectional elevation along approximately line 2—2 of Fig. 1,

Fig. 3 is a front end elevation with parts 35 of the casing removed,

Fig. 4 is a cross section through the front portion of the machine, and

Fig. 5 is a side elevation with a part of the casing removed.

Small check writers for personal or desk use involve certain limitations in size and cost which preclude the use in them of multiple setting mechanism whereby the entire and exact amount of the check containing a plurality of figures may be printed at a single printing operation. Consequently, in a check writer of the sort where each digit is printed individually, it is particularly desirable that it be possible to set the type for the printing of the successive digits quickly

and with certainty. The present invention attains this advantage and provides a device which, while desirably small and compact, is at the same time sturdy and durable, susceptible of embodiment in an attractive design, and operable with maximum convenience.

The nature of the invention will be ascertained most quickly by reference to the illustrative embodiment shown in the drawings. A suitable frame, which also constitutes a housing for the operating parts is provided being formed as a base portion 10 adapted to rest on a suitable support and a casing portion 11 extending upwardly from the base portion and of considerably less width than the same. For a portion of its length the casing portion is separated from the base portion by a horizontal slotway 12, the base portion being closed and covered below the same by a cover plate 14. In suitable bearings formed on the opposite sides of the casing portion is journaled the operating shaft 15, which extends out of the casing on the right hand side and has connected to it the operating lever which carries the operating handle 17. Within the casing a shaft 15 carries the crank arm 18, which is connected by a link 19 with the rear end of the printing lever 20. The latter is journaled on the shaft 21, which extends transversely within the base portion, and on its forward arm carries the platen block 22. A spring 24 cooperates with the lever arm 18 to urge the operating handle 16 to the raised position as illustrated in Fig. 5, and to raise the rearward end of the lever 20.

In the forward portion of the casing 11 is journaled the type wheel 25, which rotates in a vertical plane with its periphery over the platen block 22. On its left hand side this type wheel has conjoined to it the worm pinion 26, and on its opposite side the registry teeth 27. The type wheel carries on its periphery the type characters 28. Extending longitudinally in the casing 11 is the rotatable setting worm 29, which is maintained in mesh with the worm pinion 26. The top of the casing is covered by the plate 30, which is provided with a longitudinal slot 33 opposite and

parallel to the worm, and carries the indicating scale 31 which bears characters corresponding to those of the type and arranged in like sequence in a series running parallel with the worm. Slidably mounted on the top plate 30 is the setting pawl having the handle portion 32, the pointer 34 and the worm actuating tooth 35 which is maintained in mesh with the worm 29. The setting pawl is easily slidable 5 longitudinally of the slot 33 by manipulation of the handle 32, incident to which operation the worm 29 is rotated by virtue of the operative engagement of tooth 35 therewith. Rotation of worm 29 rotates type wheel 25 through the medium of worm pinion 26. The gear relationship of worm 29 and pinion 26 and the arrangement of the indicator characters on the scale 31 and of the type characters on type wheel 25 are all such that when the setting 10 pawl is positioned with the pointer in indicating relationship to one of the characters on the scale, the type character corresponding to said indicator character is positioned at the printing point above the platen block 22. 15 With a type character in printing position, depression of the operating lever 16 will swing printing lever 20 to raise the platen block 22 into cooperation with the type character at the printing point, so that an impression 20 may be made by the latter upon a sheet of paper or the like between the two. The type face and the impression surface of the platen block 22 may be serrated or otherwise formed to macerate or indent the paper by their coacting 25 pressure. In order to insure accurate registry of the type character at the printing point, I provide a registry mechanism which functions automatically as a preliminary to the printing operation. This mechanism includes 30 the registry teeth 27 which are arranged in the form of a pinion on the side of the type wheel, and the slide 36 which is pivotally connected to the lever arm 18 at its rear end and carries at its forward end a lug 35 or key 37, said slide being guided for sliding movement on the type wheel shaft. The end surfaces of adjacent teeth 27 are associated in converging relationship and terminate at radial slots 27^a between the teeth. The lug 40 45 37 is adapted to register accurately in the slots 27^a. Upon depression of the lever 16, the slide 36 is moved rearwardly, and if the position of the type wheel is such that a type character is not accurately positioned at the 50 printing point, the lug will engage the sloping end of one of the teeth 27, and cam the wheel around until the character is in the proper position, whereupon the wheel is held against rotation in either direction by the engagement 55 of the lug 37 in the cooperating slot 27^a. Such adjustment of the type wheel takes place, of course, before the platen block 22 presses the type character, so that the latter is accurately positioned before the printing 60 operation is effected, and as a necessary pre-

liminary thereto. Upon release of the handle, the operating lever is restored to the elevated position, the platen block lowered away from the type and the lug 37 withdrawn from the registry teeth, leaving the type wheel free for 70 the next adjusting movement.

For inking the type I provide an inking roller 38 which has a covering of absorbent material. This roller is rotatably mounted on an axle 39 which is carried in a swinging door 40 that is mounted on a pintle hinge 41 in position to close a side opening 42 (see Fig. 2) in the casing. The size of the opening and the relationship of the roller 38 and the door 40 are such that when the door is swung around to open position, the roller is swung outwardly through the opening to a position exterior of the casing where the ink may be applied to it. A coiled spring 44 urges the door toward the closed position and maintains the roller 38 pressed against the periphery of the type wheel, as illustrated in Figs. 4 and 5, so that incident to the rotation of the type wheel the printing characters will be rolled over the inking roller and receive the 80 applications of ink.

Any suitable mechanism may be provided for feeding the sheet of paper progressively between the successive printing operations. The arrangement illustrated in Fig. 3 comprises a feeding roller 45 which is mounted in the base in such position that its periphery extends above the plate 14, the latter being apertured to accommodate it. Above the roller 45, on the casing 11, is pivoted a lever 46 carrying at its lower end a pressure roller 47 adapted for cooperation with the periphery of the roller 45. A spring presses the lever 46 to swing the roller 47 toward the roller 45, but the pressure roller may be lifted by depression of the outer arm of the lever 46 to permit the insertion of the sheet of paper between the rollers. The roller 45 carries a number of studs 48 projecting from one end and spaced equally about its axis. On the front end of the printing lever 20 is mounted a laterally extending bracket 49 which carries a pawl 50 arranged for engagement with studs 48, and in a bracket mounted on the base 10 is mounted a spring-pressed holding dog 51 also arranged for cooperation with studs 48. When the forward end of the printing lever is swung upwardly in the printing operation, the pawl 50 will be carried upwardly and will be cammed leftwardly against its spring by cooperation of its sloping upper margin with an upper adjacent stud 48, so that the pawl will escape past the stud and then spring back to the position illustrated in Fig. 3. Meanwhile, the roller 45 is held against reverse rotation by engagement of another of the studs against the ends of the holding dog 51. This is the position of the parts at the time of the printing operation, the roller 45 then being stationary. When the 115

forward end of the printing lever is swung down by the action of spring 24, the pawl 50 will engage the stud 48 over which it was recently cammed, and will rotate the roller 45 as the pawl is carried down with the bracket 49, the preceding stud 48 meanwhile escaping past the holding dog 51. In this fashion the roller 45 is rotated a certain distance after each printing operation, and by virtue of its engagement with the sheet of paper under pressure of roller 47, will advance the paper leftwardly a proper distance to receive the next printing impression in the desired relationship with those preceding. Adjustable margin guides 52 are provided to guide the sheet of paper in proper relation to the printing line.

In operation of the device, therefore, the actuating lever 16 being in the raised position shown in Fig. 5 and the printing lever in the corresponding position with its forward end swung down, for the printing of a check or the like, the lever 46 is depressed to raise the pressure roller 47, and the sheet of paper 25 is inserted in the slot 12 and its top margin positioned against the guides 52, the sheet resting on the plate 14. The handle 32 of the setting pawl is then engaged by the left hand and moved along the slot until the pointer 30 23 registers with the character on the scale 31 which it is desired first to print. This movement of the setting pawl rotates the worm 29, worm pinion 26 and type wheel 25 to the extent and positions such as to bring the 35 corresponding type character to the printing position over the platen block 22. The actuating lever 16 is then depressed by manipulation of the handle 17 with the right hand.

This moves the registry slide 36 rearwardly, 40 so that the lug 37, by cooperation with the teeth 27, positions the type wheel in fixed position. At the same time the printing lever 20 is swung by virtue of its connection with the actuating lever through the medium of link 19, crank arm 18 and shaft 15, so that the platen block 22 is raised toward the type wheel. As the platen block passes through the aperture in plate 14, it engages the under 45 surface of the strip of paper and carries it up and presses it against the type face, thus producing the printing impression on the paper. With this elevation of the forward end of the type lever, the feeding pawl 50 has been elevated to a position above one of the studs 48, as shown in Fig. 3. Upon release of the handle 17, the actuating lever 16 is swung upwardly and the printing lever 20 is swung to remove the platen block 22 downwardly from cooperation with the type wheel, thus freeing the paper from engagement with the type. Thereupon the feeding pawl 50 engages the associated stud 48 and with the continued movement of the type lever rotates 55 the feeding roller 45 to advance the strip

leftwardly a definite distance. The setting pawl may then be adjusted to the next character and the cycle of operations repeated until the desired legend has been printed in full. With the rotation of the type wheel, 70 the type characters receive applications of ink from the roller 38 each time they pass it.

One of the distinct advantages of the apparatus resides in the ease and rapidity with which it may be operated, and one of the factors which contributes to this advantage is the convenience and visibility of the setting device and indicator scale. The entire scale is visible at all times, and the setting pawl may be moved directly and with accuracy to the desired character on the scale without the inconvenience of having to watch for the character to come up, as is the case where the scale is rotated. Accordingly, although the type characters are printed individually and successively, the writing of the check may be accomplished quite expeditiously. It will be understood that whereas I have referred above to individual type characters, that such term is not to be construed as implying in all instances a single digit or letter, but rather the character or impression printed at a single stroke of the printing mechanism.

What I claim is:

1. In a check writer, in combination, a rotatable type wheel, type characters distributed thereon, a platen movable into cooperation with the type character in printing position to print therefrom, a pinion connected with the type wheel, a rotatable worm for actuating the pinion, a manually operable pawl movable longitudinally of the worm to rotate the same, and indicating characters corresponding to the type characters distributed along the path of the pawl.

2. In a check writer, in combination, a platen, a type wheel rotatably mounted in cooperative relationship with the platen, a rotatable worm extending at an angle to the type wheel axis and geared to the type wheel, type characters arranged on the type wheel, a setting pawl having operative connection with the worm and manually movable longitudinally thereof to actuate the same to position the type characters selectively for cooperation with the platen, an indicator cooperating with the setting pawl to indicate the type character in printing position and means for feeding a sheet across the type wheel in a direction longitudinally of its axis.

3. In a check writer, in combination, a rotatable type wheel, type characters arranged thereon, a rotatable worm having gear connection with said wheel, and a setting pawl having operative connection with the worm and movable manually longitudinally thereof in a transverse direction relative

to the type wheel axis, to effect rotation of the type wheel.

4. In a check writer, in combination, a rotatable type wheel, a worm pinion conjoined thereto, type characters carried by the type wheel, a rotatable worm meshing with the worm pinion and fixed against longitudinal movement relative thereto, and a setting pawl meshing with the worm and manually movable longitudinally thereof to rotate the same.

5. In a check writer, in combination, a frame, a rotatable worm and a rotatable type wheel mounted in the frame in fixed relationship to each other, a gear connection between said worm and wheel whereby the latter may be rotated by rotation of the former, type characters carried by the type wheel, a setting device movable longitudinally of the worm and having meshing cooperation therewith whereby the worm may be rotated, and a platen mounted on the frame and movable into and out of printing cooperation with the type characters.

6. In a check writer, in combination, a rotatable type wheel, type characters carried thereby, a platen for printing cooperation with one of said characters at the printing point, actuating means for effecting printing cooperation of the platen and type wheel, a worm having gear connection with the type wheel whereby the latter may be rotated by rotation of the worm, a setting device movable longitudinally of the worm and in mesh therewith to effect its rotation, and means operable by the actuating means for locking the type wheel against rotation.

7. In a check writer, in combination, a rotary type carrier, printing type carried thereby, a housing for the type carrier, said housing provided with a wall aperture, a swinging door for closing said wall aperture, an inking roller rotatably mounted on said door to swing into and out of the housing through the wall aperture, said door and type carrier associated in such relationship that the roller contacts the type carrier when the door is in a closed position, and a spring cooperating with said door to urge the same in the closing direction and press the roller upon the type carrier.

8. In a check writer, in combination, a housing, a worm rotatably mounted in the housing, a rotatable type wheel mounted in fixed association with the worm within the housing, gearing connections whereby the type wheel is rotated by rotation of the worm, type characters arranged about the periphery of the type wheel, a platen arranged for printing cooperation with the type character at the printing point, an actuating member manually operable externally of the housing at the right-hand side thereof for effecting printing cooperation of the platen and wheel, a setting device manually operable externally

of the housing at the left-hand side thereof and effective to rotate the worm, and a scale displayed on top of the housing in indicating association with the setting device and between the latter and the actuating means, said scale comprising characters corresponding to the type characters.

9. In a check writer, in combination, a housing, a type wheel rotatably mounted therein, a worm rotatably mounted in the housing in fixed association with the type wheel and extending across the axis thereof, a worm gear connected with the type wheel and meshing with the worm at one side of the wheel, type characters carried by the type wheel, said housing provided with a slot running longitudinally of the worm, and a setting device slidable longitudinally in said slot and having a manually engageable portion exterior of the housing and a part meshing with the worm within the housing.

10. In a check writer, in combination, a housing, a type wheel rotatably mounted therein, type characters carried by the type wheel, a worm pinion conjoined to the type wheel, a worm rotatably mounted in the housing in fixed association with the worm pinion, a scale displayed on the exterior of the housing and including characters corresponding to the type characters, and a manually operable setting device having meshing engagement with the worm within the housing, and a pointer for cooperation with the scale exterior of the housing.

11. In a check writer, in combination, a housing, a worm rotatably mounted in the housing, a type wheel mounted in the housing for rotation in a plane parallel to the axis of the worm, a worm pinion conjoined to the type wheel and meshing with the worm, type characters carried on the periphery of the type wheel, a platen for cooperation with the type wheel, a manually operable actuating device for the printing mechanism, said actuating device movable in a plane parallel to the axis of the worm, and a setting device manually operable in a plane parallel to the axis of the worm and having meshing cooperation with the latter whereby it may be rotated to rotate the type wheel.

In testimony whereof I have hereunto subscribed my name.

DAVID W. JOHNSON.
